FIG. 1

FIG. 2

FIG. 3

FIG. 4

FIG. 5

FIG. 6

FIG. 7

FIG. 1 is a perspective view of a table showing my design;

FIG. 2 is a top view of the table as shown in FIG. 1;

FIG. 3 is a bottom view of the table shown in FIG. 1;

FIG. 4 is a front view of the table, which is identical to the back view since the table is symmetrical about a longitudinal axis;

FIG. 5 is an elevation view as seen from either end of the table;

FIG. 6 is a sectional view of the table taken in the plane represented by the line VI-VI in FIG. 5; and

FIG. 7 is a sectional view of the table taken in the plane represented by the line VII-VII in FIG. 4.

I claim:

The ornamental design for a table, as shown.
